CONNECTER DEVICE

John A. Meyer, North Bergen, N. J., assignor to Monroe Schottenfels doing business under the firm name and style of Henry Schottenfels, West New York, N. J.

Application November 9, 1936, Serial No. 109,829

2 Claims. (Cl. 24—198)

This invention relates to connector devices, more particularly, although not exclusively, intended for garters, brassières, and other wearing apparel.

5 A principal object of my invention is the provision of a connector device which will permit attachment thereto of an elastic strap by insertion of a loop portion of such elastic strap into the connector device in a convenient manner, 10 and by holding said loop portion in such manner that it cannot disengage itself from the connector device.

Heretofore it has been customary to thread into an elongated slot of a connector device, an 15 elastic strap or the like and then sew the free end of the strap to the strap proper so as to form a loop. This method has consumed a great deal of time in the manufacture of garments such as brassières and also in the manufacture of garters 20 and the like, and because of my invention these connecting elastic straps may be made separately in large quantities having the required loop and then such looped straps are supplied to an operator whose work it is to assemble the various 25 parts of an article of wearing apparel or other accessories. The operator merely loops into the open slot of the connector device the loop-shaped portion of the strap and after the loop has been 30 thus inserted means are provided in the connector device whereby the loop is prevented from coming out of the connector device except by intelligent guidance by the hand.

Various embodiments of my invention will be hereinafter described and shown in the accompanying drawing, and finally pointed out in the subjoined claims.

In the accompanying drawing:—

Figure 1 is a plan view of my improved connector device showing in dotted lines one looped 40 end of a strap engaging one side of the device and showing another looped end in dotted lines of a strap as it enters into the connector device;

Figure 2 is a side view of my improved device depicted in Fig. 1;

45 Figure 3 is a front view of Fig. 1; and

Figures 4 to 12, inclusive, show various modifications each embodying the invention.

Similar characters of reference indicate corresponding parts throughout the various views.

50 Referring to the drawing and more particularly to Figs. 1, 2, and 3, the connector device 15 is provided, on one side of the median line 16, with an open slot 22 and this open slot is adapted to receive the loop-shaped end of a tape or strap and 55 to hold the same in position. One end of a loop-

shaped strap 17 is shown in dotted lines in Fig. 1, and as shown in Fig. 3, the free end of this strap 17 is turned back upon itself so as to form a loop 18 and said free end is sewed to the strap 17 by stitching 19 and this loop-shaped portion 18 engages the connector device 15. The elongated slot of the connector device which is engaged by the loop 18, is provided with a node 20 which serves to press the tape or strap, as shown in dotted lines, against the leg 21 of the connector device, and this leg 21 is provided with a curved portion 23, so that under the natural operation of loop 17 and the longitudinal shifting of the same in slot 22, node 20 will first hold the loop by frictional engagement against the wall of slot 22 and such engagement will be additionally secured by the seating of end 24 of said loop in said curved portion 23, and the continuation of said curved portion designated as 25 will prevent the strap 17 from riding out of the slot 22. It will be noted that the extreme portion 21 of the hook-shaped portion is about in line with the median line 16. The loop-shaped portion 18 is inserted between the peak of hook-shaped portion 25 and the pointed portion 28 of member 29 and between said portions a small space exists through which the strap may be guided into said slot 22 as shown by the arrow 30. It will be noted that these parts form a secure retainer for the strap and into which the strap may readily enter. However, in order to remove the strap it is necessary to move the same by hand in a direction counter to that of the arrow 30. The parts excepting the particularly shaped hook, which have just been described, however, are not essentially new, but my present invention includes these described parts as part of the combination thereof which will be herein-after described.

By reference to the left-hand side of median line 16, an elongated slot 31 is shown in Fig. 1, and this slot 31 is restricted in its area by a node 32 facing a wall 33. Said wall 33 is provided with a curved portion 35 which terminates in a hooked portion 36, said hooked portion 36 facing a curved portion 37 of central member 29. The space shown between the hooked portion 36 and curved portion 37 is such as to permit entry of a strap or looped portion, shown in dotted lines by 38 and the insertion of said looped portion is made in the direction of arrow 39, shown in Fig. 1. When the strap or looped portion is inserted fully into slot 31, a node designated as 32 will hold the strap in position and curved portion 35 will maintain the strap in captivity or prevent it from coming out of slot 31 except by manual 50 55

operation. The space between the hooked shaped portion 36 and curved portion 37 is just about sufficient to permit the passage of the strap or loop single ply, as shown in Figure 1. As a result 5 of the arrangement shown, instead of having one of these connector devices provided with an elongated opening into which a strap is inserted which necessitates the formation of a loop on the strap, after the strap has been inserted into the 10 eyelet, by my improved form said loop-containing strap, which may be first made in large quantities, may be readily inserted in position and be maintained there against the manipulations attendant upon the connector device while in service 15 ice by the wearer.

In Figs 4 to 12 various forms of this combination connector, are shown.

As will be seen in Fig. 4, the central member 29 is bent or curved in a direction from the median line towards the right whereby strap 17 is held more securely by this curved portion designated by 40. A strap 17 may be inserted in the direction of arrow 41 and strap such as 38, may be inserted in the direction of the arrow 42. It 25 will be particularly noted that the hook-shaped portion 36 is shaped so as to point to and be in the direction of the curved portion 37 of the central member 29 which is provided with nodes 32 and 20 on either side thereof.

In Fig. 5, there is shown this combined connector and central member, in which the latter member is not curved as shown in Fig. 4, but the right hand portion of this embodiment resembles that shown in Fig. 1. In this embodiment the slots 22 and 31 are still further restricted than the same slots depicted in Fig. 1. In Fig. 5, nodes 43 are provided on portions of the connector device designated as 44 and 45 thereof. These nodes 43 cooperate with nodes 20 and 32 to hold 40 the strap portions in position. As before stated, the hooked or curved portion 36 of the leg 44 faces in the direction of curved portion 37 of central member 29.

In Fig. 6 of the drawing, legs 44 and 45 of the 45 connecting member are each provided with inwardly pointed nodes 46. Member 29 is also provided with a pair of nodes on either side thereof designated as 47, and it will be again noted that the hook-shaped portion 36 faces the curved end 50 37 of the central member 29.

In Fig. 7 a connector member is shown in which central member 29 shows nodes of somewhat flattened shape, and designated by 50 and 51, said nodes being in position opposite to that of nodes 55 52, and in this embodiment also the hook-shaped portion 36 faces curved portion 37 of the central member.

The embodiment depicted in Fig. 8 of the drawing, shows curved lugs and the space between the inner portion of these curved lugs and the central member 29 is somewhat exaggerated. Such curved portions designated as 55, permit the loops to shape themselves in curved manner as is sometimes preferred in certain uses to which 60 65 this connector device may be put. In this embodiment it will also be seen that the hook-shaped portion 36 is opposite to the curved portion 37 of the central member 29.

In the embodiment of my device shown in Fig. 70 9, the slots are oppositely arranged, that is, they have openings in opposite positions, the central member 29a of this embodiment being provided with nodes 20a and 32a and leg 44 thereof has a curved portion 35 in the uppermost part thereof.

Hook-portion 36 has a curved portion 35 and said part 36 is opposed to the curved surface 37 of the central member 29a. Leg 45 of this embodiment is positioned downwardly and shows a curved portion 35 terminating in hook 36, and it will be 5 noted that hook 36 faces in the direction of curve 37a.

In Fig. 10, central member 29b is provided with two nodes, one 32b near the upper portion thereof and one 28b near its lower portion, and it will be 10 noted that the hook 36 faces the curve 37 of central member 29b.

In Fig. 11, the connector device shows a portion on the right of its median line substantially like that shown in Fig. 1, but the left hand side 15 of said median line shows hook portion 36 facing portion 37 and when a loop is inserted into the left hand slot 31 it passes through channel 59 and is held in slot 31 by curved portion 35 of leg 44.

In Fig. 12, a structure similar to that of Fig. 1 is shown, but the hook portion 36 is considerably closer to the curved surface 37, and the left side as in Fig. 11, is immediately visible as being the side to attach the elastic loop permanently, since 25 this left side has no nodes.

In each of the embodiments, one of the eyes is intended for use with a looped strap intended for permanent connection thereto, whereas the other eye is intended for a temporary connection of a 30 looped strap, namely, for a strap which is put on and taken off during the use of the apparel.

From the foregoing, it will be seen that a connector is provided with parts known as nodes which hold an inserted strap or loop in position 35 by frictional pressure of said nodes upon the same and curved portions are provided on the legs of said connector device which hold the strap in captivity and prevent its getting out of the slot by the natural movements exercised by the 40 wearer, a particular feature of my improvement being that the sharpened portions forming the hook of the legs of the connector, are directed towards the curved portions of the central member. As a result of the correlation of parts and 45 particularly the hook-shaped portion positioned in the direction of the curved surface of the central member, the straps are held within the curved portions of said hook-shaped portion. On the other hand, the curved surface of the 50 central member of the device, permits a free entrance of the strap into the elongated slots.

My invention therefore resides in the features just described, in which two parts of my connecting device are open to permit entry and insertion of a loop-shaped strap and are so arranged and constructed as to hold this strap therein without danger of escape during ordinary wear, these parts being so arranged that it requires intelligent manipulation of the strap to remove it 60 from the connector device.

From the foregoing description it will be seen that my invention may be employed in various forms and devices, and it is clear that changes 65 may be made therein without departing from the spirit of the invention as defined in the attached claims.

What I claim is:

1. A connector device, comprising a plate body having walls spaced apart to form transverse 70 loop receiving eyes, each open at one end through one edge of the plate for lateral edgewise reception of a looped strap, said plate body having end walls and a center wall, a hook shaped portion contiguous to the edge opening of the plate con- 75.

5 nected to each of the end walls and extending transversely of the eye toward the center wall and having a curved interior seat, a node connected to a wall intermediate the length thereof within an eye, and extending into the eye and having its extremity spaced in respect to an opposite wall, said wall in conjunction with said node and hooked portion being adapted to secure the strap in said eye against accidental removal therefrom, said eye being adapted to receive the strap intended for temporary connection therewith, and a curved portion on the center wall opposed to the hooked portion of the other edge to provide an easy entrance for the strap into 10 said eye, and to provide an obstruction to the strap against accidental removal from said eye, said last named eye being adapted to receive the looped strap intended for permanent connection therewith.

15 2. A connector device, comprising a plate body having walls spaced apart to form transverse loop receiving eyes, each open at one end through one edge of the plate for lateral edgewise reception of a loop-shaped strap, said plate body hav-

ing end walls and a center wall, a hook shaped portion contiguous to the edge opening of the plate connected to each of the end walls and extending transversely of the eyes toward the center wall and having curved interior seats, nodes connected to said walls intermediate the length thereof, extending into the eyes and having extremities in spaced relation to their opposed walls within the eyes, and curved portions on the center wall opposite to said hooked portions on the 10 adjacent end walls and providing easy insertion of the looped straps into the respective eyes, said oppositely disposed curved and hooked portions being adapted to retain the looped straps against accidental removal, one of said hooked portions 15 with its opposite curved portion providing an obstruction for one of said loop-shaped straps to hold the same in permanent connection, and the other of said hooked portion and its respective curved portion arranged to provide an easy ingress and egress of the strap intended for temporary use.

JOHN A. MEYER.
